CLAIM

The ornamental design for a ringed rope pet toy, as shown and described.

DESCRIPTION

FIG. 1 is a rear perspective view of a ringed rope pet toy embodying my new design;

FIG. 2 is a front elevational view thereof;

FIG. 3 is a rear elevational view thereof;

FIG. 4 is a left side elevational view thereof;

FIG. 5 is a right side elevation view thereof;

FIG. 6 is a bottom view thereof; and,

FIG. 7 is a top view thereof.

The broken lines are for illustration only and form no part of the claimed design.
